UNITED STATES PATENT OFFICE

110,874

DESIGN FOR A TOY WAGON BODY

John R. Morgan, Oak Park, Ill., assignor to Sears, Roebuck and Co., Chicago, Ill., a corporation
of New York

Application December 24, 1937, Serial No. 73,846

Term of patent 7 years

To all whom it may concern:

Be it known that I, John R. Morgan, a citizen of the Republic of Guatemala, residing at Oak Park, in the county of Cook and State of Illinois, have invented a new, original, and ornamental design for a Toy Wagon Body, of which the following is a specification, reference being had to the accompanying drawing, forming a part thereof.

The drawing is a perspective view of the toy wagon body embodying my new design.

The side of the body not seen in the drawing is similar to the side illustrated.

I claim:

The ornamental design for a toy wagon body, as shown and described.

JOHN R. MORGAN.
